UNITED STATES PATENT OFFICE.

LAWRENCE WESLEY HORNE AND WARREN NOBLE CRANE, OF NEW YORK, N. Y.

AUTOMATIC DEVICE FOR CONTROLLING THE SPEED OF TRAINS.

1,138,109.

Specification of Letters Patent.

Patented May 4, 1915.

Application filed September 4, 1913. Serial No. 788,077.

To all whom it may concern:

Be it known that we, LAWRENCE WESLEY HORNE, a citizen of the United States, and resident of the borough of Brooklyn, county of Kings, city and State of New York, and WARREN NOBLE CRANE, a citizen of the United States, and resident of the borough of Manhattan, city, county, and State of New York, have invented certain new and useful Improvements in Automatic Devices for Controlling the Speed of Trains, of which the following is a specification.

The objects of this invention are to provide a means for controlling the speed of a moving train and for stopping the train when it becomes desirable to do so. The device is entirely automatic in its operation and requires no assistance from the engineer or train operatives.

20 The principle is that of electro-magnetic attraction which will retain the device inoperative so that a train will be subject to control by the engineer or other authorized persons during all times when the right of way is clear to the train, but when, however, for any reason the way shall be obstructed, the magnetic attraction is broken or interrupted and a pneumatic device automatically sets the brakes to a greater or less extent reducing the speed of the train to an extent that shall be predetermined.

In the best working of this invention, the device consists of two parts. The part carried by the locomotive and designed to operate thereon and therewith and the part secured and in operable relation with the rails of the track as fully described and shown, in an application filed by us on Sept. 4th, 1913, Serial No., 788,078.

40 The construction of our device, its method of operation, and the advantages to be derived therefrom, will be fully set forth as the specification progresses.

The following is what we consider the best means of carrying out our invention, and the accompanying drawings form a part of this specification, in which;

50 Figure 1, shows a side elevation of the completed device in operative position. A convenient rotating part of the locomotive or train is shown in dotted lines. Fig. 2, is a central longitudinal section through the cylinder, and shows the valve, piston, and spring in elevation. This and the two figures following are on a larger scale. Fig. 3, shows the ratchet and latching mecha-

nisms. Fig. 4, shows what we will term, a train magnet. Fig. 5, shows the friction device. This figure is in section.

Similar reference numerals indicate like parts in all the figures where they appear.

Our invention consists of devices which provide for a selective operation, and for a time element control of that operation. The selective operation is obtained by the attraction and interrupted attraction to the running rails 1, of a magnet 2. When running on ordinary hard steel rails the magnet is attracted to the rail, and held downward, and the pull of the magnet holds the rod 3 which firmly engages a valve 4 upon its valve seat 5. Against the pull of the magnet, the pressure of air from a reservoir, pump, or other desired source entering through the pipe 6 into the chamber 7, is endeavoring to unseat the valve thus an interruption of the magnetic circuit will allow the air pressure to unseat the valve, allowing air to pass into a cylinder 8. Arranged in this cylinder is a piston 9, under the pressure of a spring 10. The entrance of the air into the cylinder tends to compress the spring and force the piston away from the air inlet.

Connected to the piston rod 11, and operable therewith is a bar 12, and pivotally supported upon the bar 12, is a counter-weighted dog 13. The purpose of which shall appear later.

Conveniently arranged adjacent to the cylinder 8, we have provided an air pipe 14 connected with the train line air pipe, and arranged in this pipe 14, is an exhausting valve 15, upon the stem of which is a counter weighted sextant 16, provided with a number of teeth 17. The movement of the bar 12 will cause the dog 13 to engage one of the teeth 17, and the sextant will be operated and the valve opened to the extent of the movement of the bar 12. The movement of the bar 12 is however not sufficient to open the valve 15 by a single movement of the bar as will be fully explained. By the movement of the bar 12, the latch 20 will be released from the angle block 19 carried by the bar 12, and will engage one of the teeth 17 of the sector 16. The movement of the bar will continue until the enlarged portion or butt 21 which is shown as formed integral with the bar 12, engages a weighted and enlarged extension

22, formed integral with or rotatably secured to the latch 23, releasing the latch 23 from the projection 24 of the rod 3. Now assuming that the train carrying this device is in motion, magnet 2 will be passing over a magnetic section of rail, the valve 4 will be closed by attraction to the rail and the spring 10 will slowly urge the piston in a reversed direction by forcing the air 5 out of the cylinder through a small port 18 and a counter weight or spring may be provided to close the valve 15 and return the sextant to the position shown in Fig. 1. Should a second dia-magnetic section be 10 reached before the complete return of the piston, the valve 4 will again be lifted and engaged upon the latch 23, and the piston will receive a second impulse which will cause the dog 13 to engage another tooth 15 of the sector 17, opening the valve 15 and 20 setting the brakes of the train.

In Fig. 3, we have shown the bar 12 and parts attached thereto as they will appear after the first impulse. Here the latch 20 is 25 shown engaged with the sector 16, and it will readily be seen that a second impulse to the piston 9 and bar 12 when the parts are so arranged would cause the dog 13 to engage a tooth 17, that would insure that 30 the valve 15 would be fully opened. We may arrange so that it will only require two interruptions of magnetic circuit and two openings of the valve 4, and the impulses of the piston 9 to open the valve 15, or we may 35 arrange that it will require a number of such interruptions and impulses.

It is desirable that when the movement of the train is reversed or the train is run backward, our automatic device shall become inoperative, and to that end we have provided a valve 30 operated by a weighted lever 31, connected to this lever 31, is a link 32, which terminates in a lug 33 formed integral with a friction disk 34. This disk is 40 rotatably and loosely mounted upon a shaft 35, which may be any convenient rotating shaft of the locomotive or train. Secured upon the shaft 35, we have arranged a member 36, having an outwardly extending annular flange 37, and upon an inner face of the flange 37, we secure a disk of fiber or any other suitable material as indicated at 45 38. This disk 38 bears against one side of the friction disk 34, and against the other side of the disk, we arrange another fiber disk 39, which is secured to and mounted on a movable member 40. A spring 41 which bears between the movable member 40, and a convenient flange or projection 42 formed 50 integral with or secured to the member 36, tends to urge the fiber disks 38 and 39 into close and intimate contact with the friction disk 34. When the train is running ahead, the friction disk will be retained in the position shown in Fig. 1, but when the train is 55

reversed, the friction disk, the link 32, and the valve lever 31, will be conditioned as shown in the dotted lines. This motion of the valve lever closes the valve 30, and makes our device inoperative, as air cannot enter to lift the valve 4, even though the magnetic circuit be broken.

We have set forth that a dia-magnetic section of a rail, would allow our device to operate. It may, however, be desirable that 75 the device shall not operate when passing a normally non-magnetic section. Therefore, we have devised certain means for magnetizing a dia-magnetic rail section or rather for completing the magnetic circuit while a 80 train is passing over a non-magnetic section. The means for establishing a magnetic section at will, are fully described in another application. This means, however, utilizes a peculiarly shaped and laminated 85 train magnet, and as this magnet controls to a certain great extent, the operation of the valve 4 and all of the parts here described, except the valve 30, the friction clutch and parts connecting them together, we show the 90 magnet in Fig. 4. Here, the magnet is shown in end elevation, and it will be observed that it is an inverted U in shape, though having the laminations at one side projecting in an uneven line. This is intended to 95 equalize the air space on the side of a rail that must be free for the flange of a wheel but we have merely shown this method for reducing the air gap for the sake of convenience, although we may accomplish it in 100 a different manner.

We desire to call particular attention to the speed control that may be obtained with our device. When the magnet 2 passes over a non-magnetic section of rail, the valve 4 may lift, to be retained by the latch 23 until the projection 21 disengages the latch when the valve 4 will again be reseated and the piston 9 may return without affecting the brakes. If, however, a second dia-magnetic 105 section shall cause the valve 4 to operate before the elapse of a specified time, the valve 4 will again lift, causing the dog 13 to open the valve 15. If, however, the speed of the train is reduced so that the second 110 dia-magnetic section is not reached until the piston 9 has fully returned, the second operation of the valve and the consequent operations of the piston and parts attached thereto will be no more effective than the first 115 operation and no automatic setting of the brakes will take place. All of our parts may be so conditioned and arranged that the space of time between the lifting of the valve 4, and the return of the piston 9, will 120 exactly represent the allowed time for traversing the distance between the dia-magnetic or manganese sections. To assure that the train will stop at a given point it will only be necessary to arrange dia-magnetic sec- 125 130

tions closely adjacent so that the piston 9 will return but sufficient distance between the sections to allow the dog 13 to ratchet the valve 15 fully open with the second or 5 any subsequent impulse and operation of the piston 9.

It is obvious that modifications may be made within the scope of the appended 10 claims without departing from the principle or sacrificing the advantages of this invention. The automatic return of the valve 4 and resetting of the brakes may be dispensed with if desired, if omitted however it will be necessary to manually reset the valve 4 to 15 free the brakes.

Although we have described the magnet 2, as a permanent magnet having one downwardly depending side, terminating in an even line, and another side, the laminations 20 of which terminate in an uneven line, so as to equalize the air gap, we desire it understood that an electro-magnet may be used or that any other means for providing an efficient magnet may be employed.

25 Having carefully and fully described our invention what we claim and desire to secure by Letters Patent is:—

1. A device for controlling the speed of trains comprising a valve adapted to be 30 opened by a fluid pressure and a non-mechanical means for closing said valve and retaining it temporarily closed, a piston operated upon the opening of said valve, means for retaining said valve temporarily open, 35 and means operated by said piston for disengaging said temporarily retaining means, and allowing said valve to be closed.

2. A device for controlling the speed of trains comprising a piston, a fluid pressure 40 supply for said piston, a valve for controlling the admission of fluid pressure to said piston, a magnetic means for retaining said valve normally closed, mechanical means for temporarily retaining said valve open, means 45 operable by said piston for disengaging said mechanical means to allow said valve to close, and a secondary valve adapted to be operated by the movement of said piston as and for the purpose set forth.

50 3. A device for controlling the speed of trains comprising a piston, fluid pressure supply for operating said piston, a valve, controlled by a non-mechanical means adjacent to a track, for admitting air to said 55 piston, a second valve controlled by the movement of said piston and provided with means adapting it to be opened to a greater extent by each movement of said piston after the first.

60 4. A device for controlling the speed of trains comprising a pipe for supplying air under pressure, a mechanically operated

valve within said air pipe, and an electrically operated valve within said air pipe and a piston controlled by the operation of said 65 valves, an additional valve adapted to be operated by the movement of said piston and means connected to said piston for ratcheting said last named valve to an open position by a series of operations of said 70 piston as herein specified.

5. A device of the character described comprising a train line air pipe, automatic means for exhausting said train line air pipe, and automatic means operated by a rotating 75 part of said train for making inoperative said automatic means during a reversed movement of the train.

6. A device of the character described comprising a train line air pipe, having a 80 valve and means for operating it, a cylinder and piston operable therein, a bar secured to said piston and extending parallel therewith a ratchet and dog supported by said cylinder and operable by said bar for controlling said valve, and a magnetically operated valve having its seat formed integral with said cylinder, and controlling the operations of the piston as herein specified and for the purpose set forth. 90

7. A device of the character described comprising a source of air supply, a magnetically operated valve arranged to control said air supply, a mechanically operated valve arranged to control said air supply, 95 means connecting said mechanically operated valve to a rotating part of a train to open said valve upon a forward motion of said train and to close said valve on the reversed motion of said train, in combination with a piston operated by said air supply and controlled by the said valves, and an additional valve arranged in a train line air pipe, said additional valve having means by which it may be opened through a series of 100 steps by a plurality of operations of said piston as and for the purpose set forth. 105

8. A device for controlling the speed of trains comprising a piston, means for operating it, a valve adapted to be operated by 110 said piston, and a means for obtaining a second operation of said piston and a further movement of said valve before the return of said piston from the first operation causing it to operate said valve by the second operation. 115

Signed at New York city, in the county of New York and State of New York this 29th day of August 1913.
